UNITED STATES PATENT OFFICE

CHARLES S. HOWE, OF LOS ANGELES, CALIFORNIA, ASSIGNOR TO LOS ANGELES TESTING LABORATORY, OF LOS ANGELES, CALIFORNIA, A CORPORATION OF CALIFORNIA

PROTECTIVE HOOD FOR OIL AND GAS WELLS

Application filed February 11, 1929. Serial No. 339,037.

This invention relates to improvements in protective hoods for oil and gas wells, and refers more particularly to a hood or enclosure which may be lowered over the mouth of the casing so that workmen can cap the well which has "blown in" at high pressure and where there is constant danger of ignition or where the gas has already become ignited and is burning.

10 Fig. 1 is a sectional view of the lower portion of the derrick showing the hood in position to be lowered.

Fig. 2 is a plan view of the apparatus shown in Fig. 1.

15 Fig. 3 is a view taken along the line 3—3 in Fig. 1.

The primary purpose in the present invention is to furnish a hood or enclosure which may be lowered over the mouth of the 20 well casing so that men may work inside of the enclosure and cap the well.

The preferred form of the invention consists of a metal shell 1 made preferably in the shape of a hollow, truncated cone, and 25 this is suspended within the derrick 2 in a convenient position over the well which is being drilled.

The truncated cone has a double wall surrounding it, furnishing an insulated air 30 space or a space which may be filled with insulation as shown at 3. The hood or cone is supported from the top of the derrick by tackle such as that shown at 4. Guides 5 are attached to the sides of the cone and have 35 slide members 6 which engage the stanchion poles 7 which serve to hold the hood in position as it is raised and lowered over the mouth of the casing 8.

The platform of the derrick is surrounded 40 by a curb 9 extending up a foot or more and the cavity formed thereby may be filled with water, oil or other sealing substance so that the bottom of the hood is sealed when lowered, to prevent gas from escaping or air entering from below.

It is desirable to have the guide stanchions 7 firmly set in concrete bases 10 in order that the hood will be rigidly anchored. These guide stanchions are separate from the derrick construction unit in order that should 50 the derrick collapse they will still hold.

Two doors 11 and 11a are swung in the compartment built in the side of the hood and furnish an entrance and exit for the workmen. The top of the cone is open so that the 55 gas discharged from the casing 8 will be discharged through the top of the cone, and if the gas becomes ignited it will burn only beyond the top of the cone, permitting the men to work at the top of the casing.

When a "gasser" is brought in it takes ordinarily about ten minutes for the first gas to appear at the orifice or mouth of the casing after rumbling and emission of the mud, water, rock and other material from the hole. 60 The drillers and rig men would on first indication that the well was coming in, lower the inverted cone. When the cone is thus lowered, and the gas is discharged through the mouth of the casing it would not ignite 65 until it passed through the upper end of the hollow truncated cone.

The hollow truncated cone, as suggested, is equipped with a double door compartment so that it is possible for men in gas masks 75 to enter through the vestibule or compartment 12 without the admission of air, and cap the well. The men entering would be equipped with asbestos suits and proper protection from injury. The truncated cone 80 might also be provided with a spout to carry the gas flame higher above the well casing and remove the intense heat from around the hood.

Also it is contemplated that the truncated 85 cone or other shaped enclosure to be used in this connection could be split and made up of two parts which would be pulled over the mouth of the casing and joined to form a unit when the well came in. The invention covers 90

any type of enclosure which may be placed over the mouth of the well in order that the workmen may cap the well after the well has come into production and has become unruly due to high pressures of the gas or due to fire of a burning well.

This type of protection for oil and gas wells becomes extremely important in view of recent losses in the California field where 10 wells have been left to burn for periods of six weeks or two months before the pressure was sufficiently lowered to permit capping of the well. The loss of gas and damage to surrounding property due to the heat of the 15 burning well soon runs into a vast amount if a well is permitted to run wild for even a short period of time.

I claim as my invention:

1. A safety device for gas and oil wells 20 comprising a conical enclosure adapted to be set over the casing mouth, said enclosure having an opening at the apex thereof whereby the gas discharged from the well casing is exhausted into the atmosphere sufficiently 25 above the casing to permit workmen within the enclosure.

2. A safety device for gas and oil wells 30 comprising an insulated conical enclosure adapted to be lowered over the top of the casing, said enclosure having an opening at the apex thereof whereby gas discharged from the well is exhausted into the atmosphere from the opening in the enclosure and above the heads of the workmen within the 35 enclosure.

3. A safety device for gas and oil wells comprising an insulated enclosure adapted to be lowered over the top of the casing, said enclosure having an opening whereby gas discharged from the well is exhausted into the atmosphere from the opening in the enclosure and above the heads of the workmen within the enclosure, a compartment having an inner and an outer door in the enclosure and supporting guides adapted to direct the lowering of the enclosure over the mouth of the 45 casing.

4. A safety device for gas and oil wells 50 comprising an enclosure adapted to be set over the casing mouth, said enclosure having insulated walls and an opening whereby the gas discharged from the well casing is exhausted into the atmosphere above the heads of the workmen within the enclosure, a bottom seal for the enclosure and a compartment 55 in the enclosure having an inner and an outer door for entrance and exit of workmen without direct communication with the atmosphere.

6. A safety device for gas and oil wells 60 comprising a conical enclosure having an opening at the apex thereof, and guide stanchions arranged adjacent each side of the cone, said cone having connection with the

stanchions to raise and lower the cone vertically.

6. A safety device for gas and oil wells comprising a conical enclosure having an opening at the apex thereof, guide stanchions 70 arranged adjacent each side of the cone, said cone having connection with the stanchions to raise and lower the cone vertically, and a compartment in the cone having an inner and an outer door for entrance and exit of work- 75 men.
